WILLIAM LEWIS EVANS, OF WASHINGTON, INDIANA

RING-JOINT MACHINE

Application filed May 6, 1929. Serial No. 360,769.

This invention relates to ring joint machines and among other objects, aims to provide improved mechanism for cutting ring grooves and forcibly inserting rings on the bosses formed thereby without removing or disturbing the parts to be joined. In general, the invention aims to provide important improvements on the machines shown in my co-pending reissue applications, Serial Numbers 339,967 (original Patent 1,617,621) and 339,968 (original Patent 1,617,622), radical changes being made in the construction design to increase the output.

In the accompanying drawings,

Fig. 1 is a front elevation of the preferred embodiment of the machine;

Fig. 2 is a fragmentary vertical section through the cutter mechanism and ring assembling ram shown in the act of applying a ring;

Fig. 3 is a side elevation of the machine;

Fig. 4 is a section taken on the line 4—4 of Fig. 3;

Fig. 5 is a fragmentary front elevation of the ring assembling ram on its operating handle; and

Fig. 6 is a side elevation on an enlarged scale of a guide block for the rings.

Referring particularly to the drawings, the machine is there shown as being of the turret type, the mechanism being mounted on a vertical standard or column 10 supported on a suitable base 11. As shown in Figs. 1 and 3, a work supporting table 12 is adjustably secured to the column so that it may be raised or lowered and swung around.

Herein, the table rests on a screw collar 13 threaded into a collar 14 secured to the standard by set-screws. The upper end of the screw collar is shown as having wrench-receiving openings 15 whereby a spanner wrench may be used to make small and accurate vertical adjustments. When the table is properly adjusted, it is held in position above collar 13, by means of a set-screw or other clamping means so that it is prevented from swinging on the standard.

In accordance with the present invention, a groove cutter and ring assembling ram are mounted turret fashion above the work table

so that both of them can operate on the work or parts to be joined without removing the parts from the table. In this instance a turret arm or bracket 16 is slidably and swingably mounted on the standard 10 near the upper end (Fig. 3); a heavy coil spring 17 surrounding the standard and resting on a fixed collar 18 normally supporting said bracket in its uppermost position with its upper end abutting a fixed stop collar 19. The collar 18 is adapted to be raised and held with a set-screw to increase the compression of the spring.

The channel cutting and ring assembling mechanism are shown as being carried by the bracket 16. Herein, a cutter spindle housing 20 and gear casing 21 are made of one casting and are bolted or otherwise secured to the supporting bracket (Fig. 3). It is to be understood, however, that these parts may be made integral with the bracket.

Referring to Fig. 2, a vertical cutter spindle 22 is shown as being journaled in the housing 20. The housing is conveniently made substantially cylindrical and upper and lower bearings in the form of cylinders 23 and 24 are secured within the housing by means of set-screws or the like, suitable bearing bushings 25 being forced into the cylinders. The lower end of the lower bearing element is here provided with a stuffing box 26 and packing gland 26 to retain lubricant in the bearing.

The cutter shaft is directly driven by an electric motor 27 mounted on the upper end of the housing. Herein, a flanged cylindrical extension 28 is bolted to the upper flanged end of the housing and the motor casing is bolted to it with the motor shaft alined with the cutter shaft and connected thereto by a coupling 29. The arrangement is such that the special driving connections between the motor and the cutter shaft are eliminated.

On the lower end of the cutter shaft is screwed or otherwise secured a groove cutter 30 adapted to cut an annular groove in the parts to be joined and provide a smooth, cylindrical, ring-receiving boss. Also, a small drill bit 31 is secured in a socket in the end of the shaft and is arranged to drill a

small block-centering hole in the center of the boss.

To remove the shavings as the cutter advances into the work, there is shown a fan 32 screwed on the cutter shaft above the cutter and both the cutter and fan are enclosed within a shaving hood 33 slidably mounted on the shaft. This hood is shown as being substantially cylindrical, having a reduced lower end to concentrate the suction around the cutting teeth. The shavings are discharged through a side opening 34 and a short conduit 35 through which they are blown away from the operator. The lower end of the hood is flanged and has a series of pointed pins 36 adapted to stick into and grip the work, while a groove is being cut. The upper end of the hood is secured to a flanged cover 37 conveniently by means of screws 38 extending through narrow portions of slots 39, the arrangement being such that the screws may be loosened and the hood turned slightly to permit the screw heads to pass through the enlarged holes. Hence, the hood can be easily and quickly removed to afford access to the cutter.

When the cutter is in its uppermost position or out of engagement with the work, the lower end of the hood extends below the ends of the cutter teeth. It is supported for sliding movement on the cutter shaft and incidentally prevented from rotating by means of rods 40 screwed into bosses 41 on the cover and locked by jam nuts 43, each rod extending through a pair of alined openings in lugs or ears 44 on the housing 20 and having a nut above the upper ear to act as an adjustable limiting stop. In the present example, a sleeve 45 is threaded on each rod and extends through the hole in the lower ear, providing a spring abutment for a small compression spring surrounding the rod between said abutment and the lower face of the upper lug. The sleeves are adjustable to vary the compression of said springs, thereby regulating the necessary pressure of the shaving hood on the work, while being cut, so that the work will not slip or kick out when the cutter strikes it.

To limit the downward movement of the cutter, there is shown an adjustable stop member 46 in the form of a headed screw threaded into a lug 47 on the lower end of the housing and held properly adjusted by a jam nut. The arrangement is such that the lower end of the stop member strikes the hood cover and positively prevents further downward movement. This is important because ring grooves are often cut in relatively thin stock and must not cut through the face side.

Frequently, however, the groove is cut to within a fraction of an inch of the face side.

To feed the cutter into the work, after it is properly alined, a foot treadle or lever 48 is pivotally mounted on the upstanding ears

49 on the base and a link or rod 50 is pivoted to the lever and extends through a flared opening in an arm 51 on the bracket 16. A nut 52 having a rounded portion is screwed on the upper end of the link and is seated in a countersunk seat in the arm, the arrangement being such that the turret may swing partially around without bending the rod. The foot lever is preferably guided by a vertical fork 53 also on the base 11. Downward pressure on the treadle will lower the whole turret against the compression of the large spring 17 and feed the cutter until the stop screw strikes the hood cover.

In the present example, the ring assembling mechanism is connected by reduction gearing to be driven by the cutter shaft to apply great pressure to the rings. Herein, a worm 54 is secured to the cutter shaft between the bearings 23 and 24 and meshes with a worm gear 55 within the gear casing 21. The casing is shown as having a removable front cover plate 56 and the worm gear is fixed on a shaft 57 journaled in the opposite faces of the casing.

On the front end of the shaft is shown a crank pin 58 to which is pivoted a hand lever 59 having an integral arm 60 acting as one link of a toggle. This arm is pivotally connected to the upper ends of a pair of links 61 which are also pivotally connected to the upper end of a ram bar 62 guided to reciprocate vertically in a bearing 63 integral with the casing 21. The lower end of the bar is shown as being reduced and screw threaded and a cup-shaped ram 64 of a slightly larger internal diameter than the bosses formed by the cutter, is screwed on the bar and held in adjusted position by a jam nut 65. At the upper end of the screw threaded portion is shown a nut 66 which acts as a stop shoulder to abut the lower end of the guide bearing 63.

As shown in Fig. 1, a light coil spring 67 is preferably connected to the lever 59 normally to hold it and the ram in raised position. The crank is free to rotate and rock the lever without operating the ram. Now it will be understood that the lever is adapted to be operated initially to lower the ram by moving the links 60 and 61 until they are almost but not quite in alinement with the ram and are then in position for the crank to exert pressure on the ram. In Fig. 2, the ram is shown at the lower end of its stroke with the lever pulled down, the pressure being applied to the ram by the crank.

The construction and arrangement of the toggle arms or links are such that the ram can kick back if a ring strikes the bottom of its channel before the crank reaches the lower end of its stroke. Referring to Fig. 5, the arms are prevented from straightening in line with the ram bar by means of a cross bar 68 connecting the two links 61 and a flat end of the arm 60 to the right of the

5 pivot in Fig. 5 arranged to engage the cross bar. This prevents the toggle from moving past the position shown. The lever is pulled down to that position and held until the ring is forced on its boss. Thus, the toggle arms can yield by swinging to the right, overcoming the manual pressure on the lever.

10 Both the cutter and the ram are arranged at the same distance from the column, so that the ram may be swung directly over the ring groove. The turret may be turned by a handle 69 and is adapted to be stopped at the two operating stations by means of a segment 70 having radial stop arms 71 co-
15 acting with an elongated spring urged plate or plunger 72 on the bracket, which has substantially knife-edge contact with the arcuate edge portion of the segment. The plunger is elongated so that it can slide or move down with the turret without disengaging the latch segment.

20 The work is held in place on the table against a suitable gage 73 which may be either straight or V-shaped, depending upon whether the joint is a straight or a corner or mitre joint. After the groove is cut, the turret is swung to bring the ram over the boss and a frusto-conical guide block 74 having centering pin 75 projecting from its base, is set on the boss with the pin in the hole formed by the drill 31. An electrically welded, polygonal ring is placed on the block with its welded enlargement in a shallow groove 76 (Fig. 6). Manual pressure is then applied to the ram lever to straighten the links until end of link 60 strikes the cross-bar 68 between the links 61, and is held manually in that position when the crank pin is at the top. The crank pin revolving to the bottom position will, through the links, transfer pressure to the ram and sleeve, pushing the ring over the guide block into the groove and when the ring is seated in the groove around the boss, the joint is completed. The lever is then released and the ram returns to its highest position. The work is removed and the operations are repeated on the next joint.

25 From the foregoing description, it will be seen that the improved machine is eminently adapted to speed up the production of ring joints. It enables the operator to complete a joint very quickly without reversing the parts to be joined after the ring grooves are cut. Moreover, the operator can observe the action of the groove cutter and can make accurate depth adjustments for both the cutter and assembling ram. Further, the design of the machine is simplified so that it can be manufactured at a relatively low cost.

30 Obviously the present invention is not restricted to the particular embodiment thereof herein shown and described. Moreover, it is not indispensable that all the features of the invention be used conjointly, since they

may be employed advantageously in various combinations and sub-combinations.

What I claim is:

1. A ring joint machine comprising, in combination, a work table; a rotatable groove cutter and a slidable ring assembling ram movable toward the table; and a turret carrying said cutter and ram; and means to move the turret toward and away from the work. 70

2. A ring joint machine comprising, in combination, a work table; a groove cutter and a ring assembling ram movable toward the table; and a slidably mounted turret carrying said cutter and ram. 75

3. A ring joint machine comprising, in combination, a work table; a groove cutter and a ring assembling ram above the table; a turret carrying said cutter and ram; and a motor carried on the turret operatively connected to both the cutter and the ram. 80

4. A ring joint machine comprising, in combination, a work table; a column extending above the work table; a turret slidably and adjustably mounted on said column above the work table; and groove cutting and ring applying means on said turret to make a complete joint without moving the work. 85

5. A ring joint machine comprising, in combination, a work table; a turret above the table; a groove cutter and a ring assembling ram carried by the turret; and a motor associated with the turret and connected to rotate the cutter, and to reciprocate said ring assembling ram. 90

6. A ring joint machine comprising, in combination, a work table; a turret above the table; a groove cutter and a ring assembling ram carried by the turret; a motor on the turret connected to drive the cutter; and reduction gearing for delivering power to the assembling ram. 95

7. A ring joint machine comprising, in combination, a work table; a groove cutter and a ring assembling ram movable toward the table successively to engage the work thereon; and a motor connected to operate both the cutter and ram. 105

8. A ring joint machine comprising, in combination, a base; a column mounted on the base; a work table on the column; a groove cutter and a ring assembling ram supported by the column above the work table; power means to operate said cutter and ram; and means to lower said cutter and ram to engage the work on said table. 115

9. A ring joint machine comprising, in combination, a vertical column; a work table adjustably secured to said column; a bracket slidably mounted on the column above the table; a groove cutter and a ring assembling ram carried by the bracket and arranged to be lowered into engagement with the work; power means connected to operate said cutter and ram; a lever connected to lower the 125

130

bracket and feed the cutter into the work; and a lever connected to lower the ram to operative position over the work.

10. A ring joint machine comprising, in combination, a work table; a column above the work table; a bracket on the column; a groove cutter and a ring assembling ram carried by the bracket; and means to lower said cutter and ram to engage the work.

10. 11. A ring joint machine comprising, in combination, a base; a vertical column on the base; a work table adjustably supported on the column; a turret swingably and slidably mounted on the column above the work table; a groove cutter and ring assembling ram on said turret; a motor on the turret directly connected to the shaft; and power delivering connections between the cutter shaft and the ring assembling ram.

20. 12. A ring joint machine comprising, in combination, a frame having a vertical column; a work table adjustably supported on the column; a turret slidably and rotatably mounted on the column above the work table; a spring surrounding the column and normally supporting the turret in inactive position; a groove cutter and a ring assembling ram on said turret; a motor operatively connected to both the cutter and ram; a lever 25 to lower the turret against the resistance of said spring to feed the cutter into the work; and manual means initially to lower the ram.

13. A ring joint machine comprising, in combination, a frame having a vertical column; a work table adjustably supported on the column; a turret slidably and rotatably mounted on the column above the work table; a spring surrounding the column and normally supporting the turret in inactive position; a groove cutter and a ring assembling ram on said turret; a motor operatively connected to both the cutter and ram; a lever 30 to lower the turret against the resistance of said spring to feed the cutter into the work; and manual means initially to lower the ram to operative position including a toggle joint and a hand lever connected to one of the toggle links.

14. A ring joint machine comprising, in combination, a base; a vertical column on the base; a work table on the column; a slidably mounted turret on the column above the table having a vertical shaft housing and a gear casing therein; a cutter shaft journaled in said housing; a groove cutter on the shaft; a worm on the cutter shaft; a worm gear in the gear casing meshing with the worm; a crank on the worm gear shaft; a vertical ring assembling ram slidably supported by the gear casing; toggle links connecting the upper end of said ram to said crank; and a lever operatively connected to said toggle links initially to lower the ram.

15. A ring joint machine comprising, in combination, a base; a vertical column on

the base; a work table on the column; a slidably mounted turret on the column above the table having a vertical shaft housing and a gear casing therein; a cutter shaft journaled in said housing; a groove cutter on the shaft; a worm on the cutter shaft; a worm gear in the gear casing meshing with the worm; a crank on the worm gear shaft; a vertical ring assembling ram slidably supported by the gear casing; toggle links connecting the upper end of said ram to said crank; a motor mounted above the shaft housing and directly connected to drive said cutter shaft; and a lever operatively connected to said toggle links initially to lower the ram.

16. A ring joint machine comprising, in combination, a base; a vertical column on the base; a work table on the column; a slidably mounted turret on the column above the table having a vertical shaft housing and a gear casing therein; a cutter shaft journaled in said housing; a groove cutter on the shaft; a worm on the cutter shaft; a worm gear in the gear casing meshing with the worm; a crank on the worm gear shaft; a vertical ring assembling ram slidably supported by the gear casing; toggle links connecting the upper end of said ram to said crank; a lever integral with one of the toggle links initially to lower the ram; and means to prevent the links from being straightened whereby the joint may yield when the ram forces a ring to the bottom of its groove.

17. In a ring joint machine of the character described, a work table; a groove cutter above the work table; a vertical shaft for the cutter; a shaving hood slidably mounted on the shaft and housing the cutter; and means associated with the hood to discharge shavings.

18. In a ring joint machine of the character described, a work table; a groove cutter above the work table; a vertical shaft for the cutter; a shaving hood slidably mounted on the shaft and housing the cutter; and a fan associated with the hood to discharge shavings therefrom.

19. In a ring joint machine of the character described, a work table; a groove cutter above the work table; a vertical shaft for the cutter; a shaving hood slidably mounted on the shaft and normally housing said cutter, said hood being adapted to engage the work when the cutter is lowered; and an adjustable stop member cooperating with the upper end of the hood to limit the feeding movement of the cutter.

20. In a ring joint machine, a work table; a vertically movable groove cutter mounted above the table; a cutter shaft housing for the cutter shaft; a shaving hood slidably mounted on the cutter shaft; slidably spring urged rods supporting said shaving hood from said housing and preventing the hood from rotating with the cutter shaft; and a

screw threaded stop gage projecting below the shaft housing and adapted to strike the top of the hood when the cutter is fed into the work.

5 21. In a ring joint machine, a vertically movable groove cutter; a shaving hood slidably and removably mounted on the cutter shaft and surrounding the cutter, the lower end of the hood being adapted to engage the work and having a reduced portion around the cutter; a fan on the cutter shaft within the hood; and a discharge conduit on the side of the hood.

10 22. In a ring joint machine of the class described, a work table; a ring assembling ram above the work table; a power-driven crank above the ram; toggle links connecting the crank to the ram; and a hand lever connected to one of the links.

15 23. In a ring joint machine of the class described, a work table; a ring assembling ram above the work table; a power-driven crank above the ram; toggle links connecting the crank to the ram; a hand lever connected to one of the links; and a beveled end on one of the links to prevent them from straightening and to permit them to yield when the ram forces a ring into the bottom of the groove.

20 30. 24. In a ring joint machine, a work table; a vertical column extending above the table; a cutter and ram turret swingably and slidably mounted on the column; a stop segment for the turret on the column; and a spring-urged latch plate on the turret cooperating with the segment.

25 35. 25. In a ring joint machine, a groove cutter adapted to produce a ring-receiving boss in the work; a small drill associated with the cutter to make a hole in the center of the boss; a frusto-conical guide block having a guide pin projecting from the center of the base to be inserted in said opening, said guide block also having a groove in its guiding surface to accommodate an enlarged welded portion of a ring; and a ram to force the ring over the block and the boss.

40 45. 50. 55. 26. In a machine of the character described, a work support; a rotary cutter arranged to be fed into the work on the support; a yieldably mounted shaving hood surrounding the cutter and arranged to be moved into engagement with the work as the cutter is fed into it; and pointed projections on the hood yieldably to stick into and grip the work whereby to prevent displacement of the work while the cutter is operating.

60 In testimony, that I claim the foregoing as my own, I have hereto affixed my signature.

WILLIAM LEWIS EVANS.
